UNITED STATES PATENT OFFICE.

WILBUR J. HEMPY, OF KANSAS CITY, MISSOURI, ASSIGNOR TO HEMPY-COOPER
MANUFACTURING COMPANY, A CORPORATION OF MISSOURI.

COMBINATION LADLE AND BABBOTTING-JIG.

1,351,247.

Specification of Letters Patent. Patented Aug. 31, 1920.

Application filed December 19, 1919. Serial No. 346,009.

To all whom it may concern:

Be it known that I, WILBUR J. HEMPY, a citizen of the United States, residing at Kansas City, in the county of Jackson and State of Missouri, have invented certain new and useful Improvements in Combination Ladles and Babbottting-Jigs, of which the following is a specification.

My invention relates to combination ladles and babbottting jigs and while it may be employed to advantage in babbottting various articles, it is intended more particularly for use in babbottting the crank shaft bearings of multicylinder engines.

In its preferred embodiment, the invention embraces among other features, a bottom pouring ladle adapted to set directly upon the open flat side of the bearing to be babbottted, a die for placement within the bearing to mold the molten metal to fit the crank shaft as said molten metal runs into the bearing, and means to grip and close the ends of said bearing and prevent the molten metal from running out of said ends.

Other features will hereinafter appear, and in order that the invention may be fully understood, reference will now be had to the accompanying drawings, in which:

Figure 1 is an elevation of the device with the jaws thereof in open position preparatory to gripping and closing the ends of the bearing upon which the device is seated.

Fig. 2 is a vertical central section of the device with the jaws closed upon the ends of the bearing.

Fig. 3 is a horizontal section on line III—III of Fig. 2.

Fig. 4 is a fragmentary vertical section on line IV—IV of Fig. 1.

Fig. 5 is a horizontal section on line V—V of Fig. 2.

Fig. 6 is an inverted plan view of the device with the jaws in closed position.

Fig. 7 is a broken detail perspective view of a valve for controlling the flow of molten metal from the bottom of the ladle.

Fig. 8 is a fragmentary elevation of a modified form of the device.

Fig. 9 is a vertical section on line IX—IX of Fig. 8.

Fig. 10 is an inverted plan view of a modified form of the die.

In carrying out the invention, I employ a ladle 2 having a flat bottom 4 adapted to set directly upon the open flat side of that

portion of the bearing A formed integral with the engine block. Said bottom 4 has a pair of oppositely-disposed gates 6 through which the molten metal flows into the bearing A, and a pair of dowel pins 7 to fit with in the bolt holes B of the bearing and thus hold the ladle in proper position upon said bearing A.

The outflow of molten metal through the gates 6 is controlled by a valve 8, loosely connected to the lower end of a rod 10, so that the two plugs 11 of the valve 8 may seat squarely over said gates 6. The valve rod 10 extends upwardly through a tubular member 12 and is provided at its upper end with a knob 14, whereby said valve rod 10 may be raised to open the valve 8 against the yielding action of a coil spring 16, abutting at its upper end against the closed end 18 of the tubular member 12 and at its lower end against a collar 20 fixed to the valve rod 10.

The lower end of the tubular member 12 is secured to the upper portion of a yoke 22, fixed to the upper portion of the ladle 2. Preferably, the tubular member 12 is threaded into the yoke as shown on Fig. 2, and in order to prevent it from accidentally unscrewing, a spring washer 24 is interposed between the closed end 18 of said tubular member 12 and a handle 26 having a wire handhold 28.

The handle 26 is secured to the upper end of a hollow shaft 30, journaled upon the tubular member 12 and extending downwardly to the top of the yoke 22, upon which it is held by the washer 24 pressing downwardly on the handle 26. The lower portion of the hollow shaft 30 is provided with oppositely-disposed peripheral lugs 32, pivotally-connected to the inner ends of links 34 extending in opposite directions and pivotally connected at their outer ends to the upper ends of levers 36, fulcrumed in the bifurcated ends of an equalizing bar 38 extending through the sides of the yoke 22 and provided with a central slot 40 through which the valve rod 10 freely extends. The equalizing bar 38 is free to slide in the yoke 22, for a purpose which will hereinafter appear, but such sliding movement is limited by stops 39 carried by said equalizing bar and adapted to contact the adjacent sides of the yoke 22.

The lower ends of the levers 36 are con-

nected by pivots 37 to jaws 42, slidable upon a die 44 and having recesses 46 at their upper inner portions to clear the adjacent sides of the ladle 2 when said jaws 42 are closed 5 against the ends of the bearing A as disclosed on Fig. 2. The die 44 extends between the gates 6 and is fixed to the ladle 2 by any suitable means, screws 48 being shown for that purpose. A longitudinal 10 opening 50 is formed in the upper portion of the die 44 to receive the lower end of the ladle 2 (see Figs. 2 and 4). The die 44 is of the same diameter as the shaft to be journaled in the bearings which are babbitted 15 with the device, and said die 44 is of tubular formation to permit air to circulate freely therethrough to keep it relatively cool, so that it will quickly congeal the molten babbitt poured into the space C between the bearing A and said die 44 and thus reduce to a minimum the time required to babbitt all of the bearings of the cylinder block.

In practice, the jaws 42 are opened in order to pass downwardly at opposite ends of 25 the bearing A upon which the device is lowered until the bottom 4 of the ladle 2 rests upon the open flat side of said bearing and the dowel pins 7 pass through the bolt holes B. This positions the die 44 in proper relation to the bearing A. The jaws 42 are then caused to grip the ends of said bearing A by rotating the handle 26, which, through the intermediacy of the intervening mechanism, causes the jaws to move inwardly, and 30 not only grip the ends of the bearing as above-described but also to close the ends of said bearing and thus prevent the molten metal from running out at said ends. The valve 8 is then opened to permit the molten 35 metal to flow from the ladle 2 into the bearing A by engaging the knob 14 with two fingers and grasping the hand hold 28 and pulling upwardly on said knob against the action of the coil spring 16. After the bearing 40 has been babbitted, the knob 14 is released, whereupon the valve 8 is immediately closed by the action of the coil spring 16. The handle 26 is then rotated in a reverse direction to cause the jaws 42, to release 45 the ends of the bearing, whereupon the device is applied to another bearing of the engine block. Should one of the jaws 42 engage the bearing A before its companion, the latter may move into engagement 50 with the bearing owing to the fact that the equalizing bar 38 is free to move longitudinally, as hereinbefore mentioned.

Slotted guides 52 on the yoke 22, prevent the upper portions of the levers 36 from being bent laterally by the links 34 when the hollow shaft 30 is rotated to open or close the jaws 42.

Owing to the rapidity with which the device may be operated, all of the bearings of 60 a cylinder block, usually three in number,

can be babbitted before the molten metal in the ladle 2 congeals.

In the modified form disclosed by Figs. 8 to 10, inclusive, the construction is substantially the same as in the preferred form, 70 as evidenced by corresponding numerals with exponents "a." In said modified form the jaws 42^a are slid longitudinally upon the die 44^a by hand, instead of being actuated by the mechanism disclosed on the preferred form. In order to prevent the jaws 42^a from rotating on the die 44^a, the latter is provided at its ends with keys 45 fitting into slots 47 in said jaws, thus the recesses 46^a in said jaws are retained in proper position to permit the lower portions of the jaws to pass beneath the bottom of the ladle 2^a and engage the open ends of the bearing 75 to be babbitted.

The modified form also differs from the 80 preferred form, in that gates 44^b are formed in the die 44^a, so that the molten metal in flowing from the open bottom of the ladle 2^a will pass through said gates to the lower portion of the bearing. The gates 44^b have 85 seats 44^c to receive the lower ends of the valve plugs 8^a which when set cut off the flow of molten metal through the die 44^a. The upper ends of the valve plugs 8^a have 90 pin-and-slot connections 8^b with an equalizing member 8^e having a pin-and-slot connection 8^d with the valve rod 10^a.

Having thus described my invention, what I claim and desire to secure by Letters Patent, is:

1. In a device of the character described, a bottom pouring ladle adapted to rest upon a bearing to be babbitted, means for controlling the outflow of molten metal from said ladle to the bearing, and a member associated with said ladle and arranged to occupy the position of a shaft in the bearing to mold the molten metal to receive such shaft.

2. In a device of the character described, a bottom pouring ladle adapted to rest upon a bearing to be babbitted, a valve for controlling the outflow of molten metal from said ladle to the bearing, and a die associated with the bottom of said ladle and arranged to extend into the bearing, for the purpose described.

3. In a device of the character described, a bottom pouring ladle adapted to rest upon a bearing to be babbitted, a valve for controlling the outflow of molten metal from said ladle to the bearing, means for yieldably holding said valve in closed position, and a die associated with the bottom of said ladle, and arranged to extend into the bearing, for the purpose described.

4. In a device of the character described, a bottom pouring ladle adapted to rest upon a bearing to be babbitted, a valve for controlling the outflow of molten metal from

- said ladle to the bearing, a rod extending downwardly through the ladle and loosely secured to said valve to actuate the same, and a die associated with the bottom of said 5 ladle and arranged to extend into the bearing, for the purpose described.
5. In a device of the character described, a bottom pouring ladle adapted to rest upon a bearing to be babbitted, a valve for controlling the outflow of molten metal from 10 said ladle to the bearing, a tubular member secured to the ladle, a handle to said tubular member, a rod extending downwardly through the tubular member and secured to 15 the valve, means at the upper end of said rod whereby it may be raised to open the valve, a spring pressing said rod downwardly to normally hold the valve closed, and a die associated with the bottom of said 20 ladle and arranged to extend into the bearing, for the purpose described.
6. In a device of the character described, a ladle adapted to rest upon a bearing and provided at its bottom portion with two 25 gates spaced apart through which the molten metal flows into the bearing, and a die secured to the bottom of the ladle and extending between the gates, for the purpose described.
7. In a device of the character described, 30 a ladle adapted to rest upon a bearing and provided at its bottom portion with two gates spaced apart through which the molten metal flows into the bearing, a die secured to the bottom of the ladle and extending 35 between the gates, and elements projecting from the ladle and adapted to enter the bolt holes of the bearing to position said ladle and the die in proper relation with the bearing.
- 40 8. In a device of the character described, a bottom pouring ladle adapted to rest upon a bearing to be babbitted, a member associated with said ladle and arranged to occupy the position of a shaft in the bearing 45 to mold the molten metal to receive such shaft, and elements adjustably mounted on said member to engage the ends of the bearing and prevent the molten metal flowing from said ends.
- 45 9. In a device of the character described, a bottom pouring ladle adapted to rest upon a bearing to be babbitted, means for controlling the outflow of molten metal from said ladle to the bearing, a member associated 55 with said ladle and arranged to occupy the position of a shaft in the bearing to mold the molten metal to receive such shaft, elements adjustably mounted on said member to engage the ends of the bearing and prevent 60 the molten metal flowing from said ends, and means associated with the ladle for simultaneously actuating said elements.
10. In a device of the character described, a bottom pouring ladle adapted to rest upon a bearing to be babbitted, means for controlling the outflow of molten metal from said ladle to the bearing, a member associated with said ladle and arranged to occupy the position of a shaft in the bearing to mold the molten metal to receive such shaft, elements adjustably mounted on said member to engage the ends of the bearing and prevent the molten metal flowing from said ends, levers for actuating said elements, links for actuating said levers, and rotary 70 means for actuating said links.
11. In a device of the character described, a bottom pouring ladle adapted to rest upon a bearing to be babbitted, means for controlling the outflow of molten metal from said 75 ladle to the bearing, a member associated with said ladle and arranged to occupy the position of a shaft in the bearing to mold the molten metal to receive such shaft, elements adjustably mounted on said member to engage the ends of the bearing and prevent the molten metal flowing from said ends, levers for actuating said elements, 80 an equalizing bar associated with the ladle and to the ends of which said levers are fulcrumed, links for actuating the levers, a rotary shaft associated with the ladle and provided with means for actuating said links, and a handle to said shaft.
12. In a device of the character described, 85 a bottom pouring ladle, a die at the bottom of said ladle and arranged to occupy the position of a shaft in a bearing to be babbitted, members slidably on said die to engage the ends of the bearing and prevent the molten 90 metal running from said ends, a yoke on the ladle, guides on said yoke, levers extending through said guides and connected to the members to actuate the same, an equalizing bar extending loosely through the yoke and 95 to which the levers are fulcrumed, and means for actuating said levers.
13. In a device of the character described, 100 a bottom pouring ladle for use in babbetting bearings, a member at the lower portion of said ladle and arranged to occupy the position of a shaft in the bearing to mold the molten metal to receive such shaft, and dowel pins projecting downwardly from the 105 ladle to enter bolt holes in the bearing and thus position the ladle and said members in 110 proper relation to the bearing.
- In testimony whereof I affix my signature, in the presence of two witnesses.
